UNITED STATES PATENT OFFICE.

ALONZO B. ARNOLD, OF GLADBROOK, IOWA, ASSIGNOR OF ONE-HALF TO
J. E. CAREY, OF SAME PLACE.

NECK-YOKE.

SPECIFICATION forming part of Letters Patent No. 320,524, dated June 23, 1885.

App'ication filed September 18, 1884. (No model.)

To all whom it may concern:

Be it known that I, ALONZO B. ARNOLD, a citizen of the United States, and a resident of Gladbrook, in the county of Tama and State 5 of Iowa, have invented an improved Neck-Yoke and Pole-Coupling, of which the following is a specification.

My invention consists in the peculiar construction and combination of a pole-tip, a duplex pintle, and adjustable clips with the pole of a vehicle and a neck-yoke bar, as herein-after fully set forth, in such a manner that the bar and straps or chains attached thereto can swing back and forth and up and down, and 15 vibrate horizontally and also at right angles relative to the pole, as required to accommodate itself to the movements of the pole and the horses, and to prevent the pulling and jerking of harness and animals incident to the 20 use of neck-yokes.

Figure 1 of the accompanying drawings shows the pole-tip, the pintles, and clips, and a section of a bar combined. Fig. 2 is a transverse section taken through the line *x x* of 25 Fig. 1. Fig. 3 is a perspective view of the complete device on the end of a pole.

Jointly considered, these figures clearly illustrate the construction, application, and operation of my complete invention.

30 A represents a metal pole-tip, that may vary in size as desired. A leather lining is placed inside to prevent noise.

B B are pintles formed integral with a flat and perforated center, C, adapted to be pivoted to the pole-tip.

35 D is a metal strap riveted or otherwise fixed to the front and top portion of the pole-tip.

F is a bolt that extends through the pole-tip, the duplex pintle, and the strap D.

G G are clips that have eyes at their centers, adapted to admit the pintles B, and also adapted to be clasped around and fastened to a neck-yoke bar H, as clearly shown in Fig. 1. The bars H are usually turned on a lathe, and have grooves to admit the clasping ends 45 of the clips, and the space between such grooves often varies. By simply sliding the clips in or out on the pintles they can be readily adjusted to such varying spaces between the grooves of the neck-yoke bars.

50 I am aware that neck-yokes and pole-couplings have had the same number of joints, so that the parts could move relative to each other, the pole, and the horses in a similar manner; but my manner of constructing and connecting adjustable clips with a duplex pintle and a pole-tip, to adapt the complete device to be combined with yoke-bars having 55 annular grooves to receive the clips, is novel and advantageous.

50 I claim as my invention—
The improved neck-yoke and pole-coupling composed of the pole-tip A, having a brace, D, the duplex pintle B B C, the bolt F, and the open clips G, adapted to be fixed to 60 yoke-bars having annular grooves and provided with eyes at their lower ends, to be thereby adjustably and detachably connected with the pintles B, substantially as and for the purposes stated.

ALONZO B. ARNOLD.
